Attorney.

UNITED STATES PATENT OFFICE.

HANS HENRIK BLACHE, OF COPENHAGEN, DENMARK.

PISTON ROD FOR DOUBLE-ACTING INTERNAL-COMBUSTION ENGINES.

Application filed July 5, 1921. Serial No. 482,572.

To all whom it may concern:

Be it known that I, HANS HENRIK BLACHE, citizen of the Kingdom of Denmark, residing at Copenhagen, Denmark, have invented certain new and useful Improvements in Piston Rods for Double-Acting Internal-Combustion Engines, of which the following is a specification.

In double-acting internal combustion engines, it is well known to supply and carry away the cooling-water through a boring in the piston-rod. Where the piston-rod passes through both the top and the bottom covers of the cylinder, it is well known to provide the piston-rod with a central boring in such a manner that the cooling-water is pumped through the piston-rod and piston from one end to the other. Where the piston-rod does not pass through the top and bottom covers of the cylinder, it is also known to use such a central boring through the piston-rod, but in such case the central boring is provided with a pipe arranged in such a manner in the centre of the boring that the cooling-water is supplied through the pipe and carried away through the annular channel between the pipe and the walls of the boring.

The above mentioned constructions have, however, the defect that the walls of the piston-rod are too thick and the cooling of the surface of the piston-rod is therefore not sufficiently effective.

The present invention relates to a constructional form in which the above-mentioned defect is obviated the cooling-water being carried through the piston-rod in such a way that it passes through the rod near the surface. The cooling of the rod near the surface is of the greatest importance, because the piston-rod passes out through the cylinder cover through a stuffing-box, which is packed with a suitable packing. The piston-rod must therefore be covered by a thin film of oil to prevent leakage through the stuffing-box and also to prevent scratching of the surface of the piston-rod. The above mentioned oil-film cannot be present unless the surface of the piston-rod is sufficiently cool to prevent the oil from being consumed by the hot gases.

In the drawing is shown a constructional form of the invention.

Fig. 1 is a side view, with the piston proper and cross-head in section.

Fig. 2 is an enlarged end view of the piston-rod.

The piston-rod *a* is provided at both ends with reduced portions or stems *b*, whereby it is connected at one end to the piston *f* 60 and at the other end to the crosshead *h*. The piston-rod *a* is provided with a central boring *c*, and also with an annular series of smaller borings *d* which are situated directly under the surface of the piston-rod in such a manner that the rod will be effectively cooled by the cooling-water which flows through the borings *d*. The piston-rod is, as before-mentioned, connected to the piston and there held in place by 65 the nut *e* (Fig. 1). In the boss at hub of the piston an annular series of passages *g* is formed, which passages register with the borings *d* in the piston-rod, said borings opening through the shoulder produced consequent upon the reduction of the rod end. 70

The cooling-water is supplied to the central boring *c* in the piston-rod, in any suitable manner, and from the boring *c* it is conducted into the piston which is hollow, thereafter leaving the piston through the passages *g* in the hub of the piston and being discharged through the borings *d* near the surface of the piston-rod and flowing out through the passages *i* in the crosshead. 80

The cooling-water may also be made to flow in the opposite direction, being supplied through the borings *d* and carried away through the central boring *c*.

I claim:

1. The combination of a piston rod having a central bore and an annular series of bores located close to its peripheral surface, all of which bores extend longitudinally from end to end of the rod; and a hollow piston having its hub mounted on one end of said rod and formed with an annular series of passages in register with the annular series of bores in the rod, the central bore of said rod opening immediately into the interior 95 of the piston, whereby the cooling fluid may be supplied to said piston through said central bore and discharged therefrom through said annular series of passages and bores, or vice versa.

2. The combination of a piston rod having a central bore and an annular series of bores located close to its peripheral surface, all of which bores extend longitudinally from end to end of the rod; a hollow 100

105

110

piston having its hub mounted on one end of said rod and formed with an annular series of passages in register with the adjacent ends of the annular series of bores in the rod; and a cross-head having an opening in which the other end of the rod is mounted and also having an annular series of passages in register with the other ends of the annular series of rod bores, the central bore of said rod opening at one end immediately into the interior of the piston, whereby the cooling fluid may be supplied to said piston through said central bore and discharged therefrom through said annular series of passages and bores, or vice versa.

3. The combination of a piston rod having a reduced portion at one end providing a stem and a lateral shoulder encircling the

same, said rod being formed with a central longitudinal bore which opens at one end through said stem and with an annular series of bores located close to its peripheral surface and opening at one end through said shoulder; and a piston having a socketed hub in which said stem is fitted and through which it projects, said hub being formed with an annular series of passages in register with the adjacent ends of the annular series of bores in the rod, whereby the cooling fluid may be supplied to said piston through said central bore and discharged therefrom through said annular series of passages and bores, or vice versa.

In testimony whereof I affix my signature.

HANS HENRIK BLACHE.
